UNITED STATES PATENT OFFICE

MAURICE E. BOSLEY, OF CHICAGO, ILLINOIS, ASSIGNOR TO THE D. W. BOSLEY COMPANY, OF CHICAGO, ILLINOIS, A CORPORATION OF ILLINOIS

WEATHER STRIPPING

Application filed August 20, 1927. Serial No. 214,370.

This invention relates in general to weatherstripping and has particular reference to an improved weather-tight gasket adapted for use in connection with movable closures for sealing the crevices between the closure members when in closed position.

My invention contemplates the provision of an improved weatherstrip of the type comprising a soft flexible core encased in a sleeve, the edges of which are extended at a side and folded and seamed together to provide an attaching flange. Such weatherstrips when arranged between closure members that compress the packing require little strength in the flange, but where the closure is against the weatherstrip without a companion member back of it, as when the pressure comes in the plane of the attaching flange, tendency is provided for the strip to give back between the points of fastening of the flange and in this event to result in an uneven pressure at these points and the spaces therebetween.

The principal object of the invention is the provision of a weatherstrip having a strengthening member disposed longitudinally therein for the purpose of maintaining a tight engagement, throughout the length of the weatherstrip, between the weatherstrip body and a closure member engaging the body in a direction parallel with the plane of the attaching flange.

A further important object of the invention is the provision of a weatherstrip having a strengthening longitudinal insert disposed in the flange thereof adjacent the body portion for the purpose of strengthening and supporting the body in operative position.

Another important object of the invention is the provision of a weatherstrip adapted to conform with, and to maintain close engagement upon, uneven or discontinuous surfaces. When weatherstripping is secured upon a closure member having warped or otherwise discontinuous surfaces, or when the weatherstrip is positioned upon a corner of a closure member, there is a tendency for the weatherstrip portions to draw away from close engagement upon the closure member and difficulty is frequently experienced in arranging the weatherstrip to maintain its en-

gaged position upon the member at points immediately adjacent the apex of the corner, the resilience of the weatherstrip causing a continuous curvature rather than a sharp bend conforming with the angle of the closure corner.

Another important object of the invention is the provision of a weatherstrip having an attaching flange in which there is enclosed a flexible stiffening member adapted to be bent into conformity with the contour of the closure member upon which the weatherstrip is secured and to maintain a close engagement of the weatherstrip upon uneven surfaces.

Another important object of the invention is the provision of a weatherstrip especially adapted for close engagement upon the angular portions of a closure member.

Another important object of the invention is the provision of a weatherstrip having a bendable insert enclosed within the attaching flange in order to maintain the flange properly in arranged position upon a closure member without using a large number of nails or similar fastening devices.

Numerous other objects of the invention will be apparent as it is better understood from the following description, which, taken in connection with the accompanying drawings, discloses a preferred embodiment thereof.

Referring to the drawings:

Figure 1 is a perspective view of a weatherstrip embodying my invention, portions of which are shown in cross-section;

Fig. 2 is a plan view illustrating the weatherstrip assembled upon a closure member, the parts being arranged to show the weatherstrip compressed by forces acting parallel with the plane of the attaching flange, and

Fig. 3 is a cross-section taken substantially on the line 3—3 of Fig. 2.

To illustrate my invention I have shown on the drawing a weatherstrip comprising a core or rope 11 formed of suitable resilient packing material and an enclosing sleeve 12, the mid-portion 13 of which is wrapped about and encloses the resilient core 11 to form a

substantially cylindrical weatherstrip body, and the edges 14 and 15 of which comprise flanges which extend laterally from the cylindrical body portion of the weatherstrip. 5 These flanges 14 and 15 engage at their junction with the body portion and extend adjacently outward. The extreme edge portion 17 of the upper flange 15 extends outwardly beyond and overlaps the outer edge of the 10 lower flange 14, and is folded back along a line of bend 16 and engages the lower surface of the flange 14 to provide an integral, outwardly extending, three-ply attaching flange 18, the fly edge 19 of the portion 17 having 15 final engagement upon the body of the weatherstrip adjacent the base of the flange 18. An insert 21 comprising a strand, roll, or rod of suitable flexible material, is enclosed within the body of the flange 18 and adjacent 20 the body portion of the weatherstrip, being inserted and positioned between the flange portions 14 and 15. The inter-folded portions 14, 15 and 17 are secured together on each side of the insert by means of a seam 22 25 formed at the base of the flange between the insert and the body portion, and a seam 23 formed in the body of the flange. These seams secure the insert in position in the flange, the seam 21 also performing the function of securing the mid-portion 13 of the sleeve about the resilient core 11 of the weatherstrip. The interfolded flange portions may also be secured together by means 30 of a seam 24 formed in the flange adjacent its 35 outer edge.

The weatherstrip is especially adapted for assembly upon a door frame 25, as shown in Figs. 2 and 3 of the drawing, in a position in which a door member 27 closes against the 40 body of the weatherstrip in a direction parallel with the plane of the flange 18. The weatherstrip is secured in position by means of nails or similar fastening devices 27, which pass through the flange at spaced intervals 45 and take into the closure member 25. It will be apparent that the portions of the weatherstrip body opposite the fastening members 27 will be supported firmly by the flange and will have a firm engagement with the closure 50 member 26, whereas in the absence of the strengthening member 21, the weatherstrip body intermediate the members 27 will not firmly engage the closure member because the flange parts, which back the resilient body 55 portion, will sag somewhat between the fastening devices. By providing the longitudinal strengthening member 21, the intermediate portions of the flange are held firmly in position against sagging and the weatherstrip body is backed up so that a uniform engagement between strip and closure member is provided.

The insert not only serves the purpose of 60 stiffening the weatherstrip body intermediate 65 the fastening members, but also provides

means for maintaining the weatherstrip flange in any position in which it may be arranged. This construction provides a weatherstrip which may be arranged in close engagement upon uneven surfaces and one, 70 which, having been disposed in a definite position, will maintain such position against the tension of the natural resilience of the weatherstrip which, after distortion, tends to resume a normally straight position and to 75 draw away from depressions or other irregularities of the surface upon which the weatherstrip is positioned. Since the strengthening member is adapted to maintain the flange properly in a definite engaged 80 position, fewer fastening devices are needed to secure the weatherstrip in place. Not only is economy of fastening devices thus effected, but since the fastening flange is weakened wherever a fastening device passes 85 through, a weatherstrip which requires fewer fastening devices to maintain it in position is inherently a more durable and satisfactory article.

It is thought that the invention and many 90 of its attendant advantages will be understood from the foregoing description, and it will be apparent that many changes may be made in the form, construction and arrangement of the parts without departing from the 95 spirit and scope of the invention or sacrificing all of its material advantages, the form hereinbefore described being merely a preferred embodiment thereof.

I claim:

1. A weatherstrip comprising a soft resilient core, a strip of material comprising a sleeve enclosing said core to form a substantially cylindrical weatherstrip body, said sleeve having engaging edge portions extending laterally from said body, one of said edges being folded back upon and enclosing the other, said interfolded edges being secured together adjacent said body to form an attaching flange extending laterally from said body, and a longitudinal strengthening member enclosed within said flange adjacent the body portion.

2. A weatherstrip comprising a resilient core of packing material, a sleeve having portions enclosing said core to provide a substantially cylindrical weatherstrip body, said sleeve having opposite engaging edge portions extending from said body, one of said edge portions being folded back upon and enclosing said other edge portion, said interfolded portions being secured adjacent said body, and a flexible strengthening member enclosed between said folded portions adjacent said body and extending substantially 110 parallel with said body.

3. A weatherstrip comprising a resilient core, a sleeve enclosing said core to provide a resilient weatherstrip body, portions of said sleeve extending laterally from said body 125

to form an attaching flange, and a bendable stiffening member enclosed within said flange adjacent said body.

4. A weatherstrip comprising a resilient core, a flexible stiffening member extending substantially parallel with said core, and a strip of material comprising an enclosing sleeve wrapped about said core and said flexible member, portions of said enclosing sleeve being secured together adjacent said core and said flexible member.

5. A weatherstrip comprising a substantially cylindrical core, a bendable stiffening member extending parallel with said core, and an enclosing sleeve wrapped about said core and said member portions of said sleeve being seamed together therebetween.

6. A weatherstrip, comprising a substantially cylindrical body, a laterally extending attaching flange, and a flexible insert enclosed within said attaching flange adjacent said body and extending throughout the length of the flange.

7. A weatherstrip, comprising a flexible core, a strip of material embracing said core and having its edges extending out at the side to form an attaching flange, and a bendable stiffening member arranged in the flange and closely adjacent said core, the parts of the attaching flange being seamed together on opposite sides of said stiffening member to retain the same in position adjacent said core.
